ABSTRACT: A mechanism for orbiting a machine member in a noncircular orbit at high speeds, such as a sliding vane in a rotary pump or engine which vane changes its position from the center of rotation of the rotor in which it is mounted outwardly and inwardly and thus changes its position for balancing. The invention utilizes a pendulum weight to alternately store and release energy to assist in restoring the sliding vane to its median balanced position.

CENTRIFUGAL FORCE ENERGY CONSERVING MECHANISM

BACKGROUND OF THE INVENTION

In my U.S. Patent 65 3,318,255 dated May 9, 1967, I have found that high-speed operation cannot be attained practically due to the tremendous centrifugal force which is generated by the noncircular path of movement of a sliding vane. For example, an orbiting sliding vane 6 inches from the center of orbit will be subjected to 1,000 times the force of gravity at only 2,400 revolutions per minute, and to move this vane inwardly would require a force of about 1,000 times its weight. This force would have to be applied once each revolution or 2,400 times per minute at 2,400 revolutions per minute, and while balancing may be accomplished by providing the same weight on the opposite side of the pivot, such balancing overcomes vibration but does not overcome the problem of centrifugal force. Rather such balancing compounds the problem.

SUMMARY OF THE INVENTION

I have overcome the above-mentioned problem of centrifugal force by converting the centrifugal force energy into potential energy which may be used to restore the body to its original radius without the need of any additional energy (disregarding friction). The mechanism which I have utilized for this purpose of storing energy in the form of potential energy and releasing it again is the pendulum which is used to apply torque in a direction on the means for moving the sliding vane as a compensation.

BRIEF DESCRIPTION OF THE DRAWINGS

FIG. 1 is an end view partly in section of the rotor and showing the balancing arrangement for one sliding vane; 35

FIG. 2 is a section on line 2-2 of FIG. 1;

FIG. 3 is an exploded detail view of the lever showing the pendulum weight as a part thereof;

FIG. 4 is a sectional view showing the rotor housing and the end plates in position with the gate or sliding vane mechanism omitted;

FIG. 5 is a fragmental end view of the cam slot in an end plate of the housing; and

FIG. 6 is a diagrammatic view showing the sliding vanes in 45 various positions.

DESCRIPTION OF THE PREFERRED EMBODIMENT

The rotating chamber mechanism here described is similar in many respects to the showing in my U.S. Pat. No. 3,318,255 dated May 9, 1967, but I have arranged a different balancing mechanism for the sliding vane. With reference to the drawings and particularly FIG. 4, there is a casing designated 10 having a circular enclosing wall 11 and end plates 12 and 13 which support ball bearings 14 and 15 in which the rotor designated generally 16 is rotatably mounted on shafts 17 and 18. The rotor has a body 19 and end flanges 20 and 21 which together with the casing 11 provide a chamber 22 of generally annular shape.

The rotor (FIGS. 1 and 2) is cylindrical and provided with a plurality of symmetrically arranged guide slots 25 extending inwardly from its periphery 26. A sliding vane 27 is located in the guide slot of this rotor. This vane is actuated by rods 28 extending thru the bottom wall 29 of the guide slot 25 (see FIGS. 1 and 2). These rods are secured to a balancing bar 30 by a pin and locking screw 40. The bar 30 extends outwardly thru the slots 31 in the flanges 20 and 21 of the rotor and is guided by the walls of these slots. A fulcrum rod 35 extends axially of the rotor 16 thru the flanges of the rotor (see FIGS. 1 and 2) upon which there is provided the lever 36 (see also FIG. 3). This lever is bifurcated at one end 37 which receives a link 38 in the bifurcation held therein by pin 39, which link 38 is rotatably connected to the balancing bar 30. A boss 41 on this lever 36 engages a bushing 42 secured to flange plates 20 and

21 to maintain the lever 36 in its desired position in a space 43 between the rotor 16 and casing 12 (FIG. 4). A pendulum weight 44 on the opposite side of the pivot rod 35 from the connection of the lever 36 to the balancing bar is provided. A cam follower 45 is secured on the lever 36 by stud 45a to enter a channel 46 of cam shape in the end plates for controlling the movement of the lever and in turn the movement of the gate 27 in its slot 25. In the median position, the weight of the balance bar plus the connecting link plus 1/2 the weight of the lever arm are designed of such a weight so as to exactly balance the sliding vane. Note that in FIG. 6 position A, all parts being designated by suffix A, the radial line of centrifugal force passes through fulcrum 35A and the center of balance of the pendulum weight 44A so the torque on the pendulum must be zero; i.e. the effective lever length is zero so zero times the weight is zero. When the sliding vane is moved out toward its fully extended position at B, all parts being designated with suffix B, centrifugal force on the vane is increased by reason of its increased radius. It is this increase in centrifugal force energy that is used to raise the pendulum weight away from its radial line of centrifugal force by means of its lever 36B. As the pendulum is lifted, centrifugal force energy is changed to potential energy. The weight of the pendulum is calculated to use all the energy available, by so doing equilibrium is maintained throughout the movement. To calculate the weight and force of the pendulum the following formula may be used: $F=RYW/L$

where

Y=Effective lever length of pendulum in inches

W=Weight of pendulum in lbs.

L=Lever arm length in inches

F=Force in inch lbs.

R=Distance center of rotation of rotor to center of balance of pendulum. The pendulum is ideal for this purpose because it has the marvelous faculty of an infinite number of increments of effective lever arm length from 0 up to maximum and hence one weight can be used to give a varying torque from 0 to its maximum in both directions + and -.

When the sliding vane reaches its fully extended position at 27B the pendulum has been raised distance Y which is the same distance as the effective lever arm length of the pendulum weight 44B. Now as the sliding vane and the pendulum moves back toward its median position as at 44A the potential energy is released in the form of a torque on lever 36B which exerts a force through the link 38 to the balance bar 30B which helps to retract the sliding vane. When it reaches the median position at 27A and 44A the torque arm length is 0 and so the torque is 0 as it should be. As it continues to move, the pendulum is raised again only this time on the other side of the radial line of centrifugal force as shown at 44C. As it moves toward this retracted position at 44C, the increased centrifugal force on the balance bar 30C provides the energy to lift the pendulum. As the pendulum is lifted, it becomes heavier, but also, as the balance bar moves out, its centrifugal force is increased. These two forces occur in the right proportion because they have a common radius. Note that distances Z and Y are the same as the movement of the sliding vane 27.

When the pendulum moves through its arc the centrifugal force thereon will diminish slightly because it moves in toward the center of rotation of the rotor only very slightly. Also its center of balance will shift slightly. These two things can easily be compensated for. There is thus described a raised pendulum containing just enough potential energy to return the balance bar and also the sliding vane to its original balanced median position without having to overcome any unbalanced condition. The cam follower roll is attached to the lever arm in such a position as to facilitate easy action, both inwardly and outwardly by the cam. Also this is the reason for the bend in the lever 36. It distorts the true lever length slightly, but in calculations the true length is the one to be used for calculation.

In operation, the pendulum moves through its median position at great speed, and so another force to be considered is

momentum of this oscillating pendulum lever. I have found it desirable to compromise between the two forces, momentum and centrifugal. If the pendulum is designed slightly heavy, then at the two extreme positions, plus and minus, this excess weight will aid in bringing the pendulum to a halt. Then when it stops, torque will aid in getting it started again in other direction. The momentum will tend to swing thru to the other side and the excess weight will not be detrimental but rather will have some advantage in the extending and retracting of the sliding vane, and a shorter cam can be used than would otherwise be practical.

I claim:

1. In a rotary mechanism, a rotor having an axis of rotation, a reciprocating member in said rotor on one side and a balance bar on the other side of the axis of rotation of said rotor, means connecting said member and bar together, said bar balancing said member in one median position, a pivot on said rotor parallel to and spaced from said axis of rotation, a pendulum like weight and lever mounted on said pivot and coupled to said balance bar to swing in a plane at right angles to said axis, said pendulum like weight and lever so positioned in relation to the center of rotation as to exert no torque and

consequently no force on the balance bar at the median position, positive torque and consequently positive force on the balance bar with the member in the extended position, and negative torque and consequently negative force on the balance bar with the member in the retracted position, the magnitude of the torque calculated so as to balance the magnitude of the centrifugal forces that act on the said member and the balance bar whereby the torque and centrifugal forces are kept in equilibrium as the rotor rotates and the member reciprocates and no additional energy is needed to overcome centrifugal force.

2. In a rotary mechanism as in claim 1 wherein the pendulum like weighed lever has its median position with its weight center of balance, its pivot, and the axis of rotation in line.

15 3. In a rotary mechanism as in claim 1 wherein the rotor is mounted in a housing and means to slide said reciprocating member comprises a cam channel in said housing and a cam follower attached to said pendulum and riding in said cam channel.

20 4. In a rotary mechanism as in claim 1 wherein said reciprocating member is a sliding vane.
